The ornamental design for a padded protective sleeve for hip restraints on golf and other transportation carts, as shown and described.

DESCRIPTION

FIG. 1 is a perspective view of a prior art golf cart with the padded protective sleeve for hip restraints on golf and other transportation carts in place showing my new design;

FIG. 2 is a perspective view of the padded protective sleeve for hip restraints on golf and other transportation carts;

FIG. 3 is a perspective view of the padded protective sleeve for hip restraints on golf and other transportation carts;

FIG. 4 is a top plan view of the padded protective sleeve for hip restraints on golf and other transportation carts;

FIG. 5 is a bottom plan view of the padded protective sleeve for hip restraints on golf and other transportation carts;

FIG. 6 is a left elevation end view of the padded protective sleeve for hip restraints on golf and other transportation carts; and,

FIG. 7 is a right elevation end view of the padded protective sleeve for hip restraints on golf and other transportation carts. The broken line showing of a golf cart in FIG. 1 is included for the purpose of showing the environment in which the padded protective sleeve for hip restraints on golf and other transportation carts is used; and forms no part of the claimed design. The broken line boundary shown in the FIG. 5 view encloses portions of the padded protective sleeve that form no part of the claimed design.
